UNITED STATES PATENT OFFICE.

GEORG RITTER, OF STUTTGART, GERMANY.

TELEPHONE SYSTEM.

SPECIFICATION forming part of Letters Patent No. 691,664, dated January 21, 1902.

Application filed November 2, 1900. Serial No. 35,271. (No model.)

To all whom it may concern:

Be it known that I, GEORG RITTER, a citizen of the German Empire, residing at Augustenstrasse 3, Stuttgart, Germany, have invented certain new and useful Improvements in Telephone Systems; and I do hereby declare the following to be a full, clear, and exact description of the invention, such as will enable others skilled in the art to which it applies to make and use the same.

My invention relates to improvements in telephone systems, and in particular to improvements in central-station switchboard apparatus.

The object of the invention is to provide means for automatically switching on the calling-current to the desired substation-line and for automatically interchanging the central-station telephone and the clearing-out annunciator in the proper sequence.

With this object in view my invention consists in the features of construction, combinations of parts, and details which will first be described in connection with the accompanying drawings and then particularly pointed out in the claims.

In the drawings, Figure 1 is a diagrammatic view of so much of a telephone system embodying my invention as is necessary to illustrate the same. Fig. 2 is a detail sectional view of one of the improved circuit-changing devices employed by me for switching the calling-current on and off the substation-line to be called. Fig. 3 is a similar view of a circuit-closer employed by me for closing the circuit of the magnet which restores the clearing-out drop. Fig. 4 is a detail diagrammatic view illustrating a modification of my invention. Fig. 5 is a detail sectional view of a circuit-closing device employed in connection with the modification shown in Fig. 4. Fig. 6 is a detail diagrammatic view illustrating another embodiment of my invention, and Fig. 7 is a similar view illustrating a further embodiment of said invention.

Referring to Fig. 1 of the drawings, S' and S² are plugs, the former being the answering-plug and the latter the connecting-plug. The latter plug S² differs from the plug S' in that it has a conductive portion s in addition to the usual two terminals, which conductive

portion is arranged to make an electrical contact with any socket or jack-ring h into which it may be inserted.

At W is shown a special form of circuit-changer for connecting the source of calling-current with the line and for cutting off the said source after a predetermined interval. This circuit-changer comprises two switches, which are identical in construction. Each consists of an outer tube w, Fig. 2, closed at each end, within which is located an inner tube w', closed at the lower end only and provided with a hole or series of holes w² near its middle, the inner tube being held in place and separated from the outer tube by cement, (indicated at w³), which extends upward to the lower edge of the said holes w². The tubes are of insulating material, preferably glass, and into the inner tube is placed some mercury w⁴. Into each end of the outer tube w and projecting into the interior of the inner tube w' are two wires, which are connected with the circuit in a manner herein-after described. These wires are indicated at s' s², Fig. 2, and are arranged to have their terminals closed by the mercury w⁴ when the latter is at the bottom of the inner tube w', as it is shown in Fig. 2. The wire s² is provided with a branch terminal s³, which projects between the inner and outer tubes and reaches nearly to the holes w². A wire r also extends through the exterior tube w and terminates near the holes w².

In the circuit-changer W a pair of switch devices such as above described is employed, each being mounted on trunnions and both being connected so as to swing simultaneously on said trunnions by means of a frame w⁵, held yieldingly in its raised position by means of a spring w⁶. The terminals s' s² of each switch device are connected to the respective terminals of the plugs S' S² by the wires n n' o o', which form the connector-conductors, while the terminals r of said switch devices are connected to the terminals of a local circuit R, containing a source of calling-current, (indicated at R', Fig. 1.)

At V is shown a main circuit-changer arranged to interchange the central-station telephone and the clearing-out annunciator in their connections with the talking-circuit,

said central-station telephone being indicated at T and the clearing-out annunciator at E. The said main circuit-changer V has two switch-arms v v' , the former being arranged to engage either the contact T' or the contact E', while the latter is arranged to engage either the contact T² or the contact E². The contacts T' T² form the terminals of the operator's telephone set, while the contacts E' E² form the terminals of the main coil E³ of the clearing-out drop E. The two switch-arms v v' are connected to the connector-conductors by the branch conductors $n^2 o^2$, the latter of which includes a circuit-breaker N, held open by the answering-plug S' and so arranged as to be closed automatically when the answering-plug is removed from its holder for insertion in the jack-ring of a substation which has called the central office. The switch-arm v' is provided with an armature v^3 , arranged to be attracted by an electromagnet M', whose coil is included in a local circuit terminating at the jack-rings h and at the conductive portion s of the connecting-plug S², the said circuit being energized by the battery P and composed of conductors $x x' x^2 x^3 x^4$. The two switch-arms v v' are connected so as to move together—as, for example, by the frame B, which carries a tongue B', pivotally connected at b to the frame B and arranged to come into contact with the frame w^5 , whereby the latter is moved by the movement of the main circuit-changer V. The said tongue B' is provided with a nose b', having an inclined surface arranged to engage an abutment A, fixed against movement in one direction and arranged to swing in the opposite direction. When the main circuit-changer V is pulled downward by its armature, the frame B moves with it, and the tongue B', which is at that time in contact with the frame w^5 , pushes the latter down against the action of its spring w^6 until the inclined surface of the nose b' engages the abutment A, whereupon the tongue B' is forced to move laterally, swinging upon its pivotal connection b. In this way the tongue B' is forced out of engagement with the frame w^5 and the latter is released, being therefore again moved to its normal position by its spring w^6 . The main circuit-changer V is also provided with a spring v^3 , by means of which it is returned to its normal position when the magnet M' is demagnetized.

To the frame B of the main circuit-changer V is connected a delay-action circuit-closer C, which in this instance comprises a switch device similar to one of those employed in the circuit-changer W, with the exception, however, that it is provided only with two terminal wires p and e^4 , which terminate near each other and near the holes in the inner tube, in the space around the said inner tube, as will be understood from Fig. 3. The wires p and e^4 , respectively, are the terminals of a branch circuit from the local circuit which is

energized by the battery P, the said branch circuit including the restoring-coils E⁴ of the clearing-out drop.

The operation of the mechanism thus far described is as follows: When the operator receives a call and lifts the answering-plug S' for the purpose of inserting it into the proper jack, the branch circuit to the main circuit-changer V is closed at the circuit-breaker N, so that when the said answering-plug S' has been inserted into its jack the central-station telephone T is in circuit with the substation-line from which the call is received over the contacts T' T², switch-arms v v' , conductors $n^2 o^2 n' o'$, and the terminals of the answering-plugs. So soon as the operator has ascertained the number of the substation to be called and inserted the connecting-plug S² in the proper jack, the local circuit from the battery P is closed by the conductive portion s of the plug S² coming into contact with the jack-ring h , and the magnet M' is energized, thereby attracting its armature v^3 and operating the main circuit-changer V to interchange the clearing-out drop E with the central-station telephone T in its connections to the talking-circuit. The said clearing-out drop will then have its main coil E³ connected to the talking-circuit over the contact-points E' E², switch-arms v v' , branch conductors $n^2 o^2$, to the connector-conductors $n' o'$. At the same time by the movement of the main circuit-changer V downward the frame w^5 of the circuit-breaker W is moved downward and then released, whereupon it is drawn upward to its normal position by its spring w^6 . Upon the downward movement of the said circuit-breaker its switch devices are tipped so that the mercury w^4 in the inner tubes w' of said switch devices is permitted to run out into the spaces between the inner and outer tubes, said mercury remaining at the ends of said outer tubes. By this action the connection between the two parts n and $n' o$ and o' of each connector-conductor is broken. Upon the upward movement of the circuit-changer W the mercury in the switch devices flows down in the spaces around the inner tubes until stopped by the cement fillings w^3 , and thereby closes the circuits through the terminals s^3 and r , thus connecting the local circuit R, containing the source R' of calling-current, with the line to be called through the parts n and o of the connector-conductors and through the terminals of the plug S². The mercury gradually flows through the holes w^2 in the inner tubes of the switch devices, thus cutting off the source of calling-current from the line connected with the plug S², and finally returns to the bottom of the inner tubes w' , again closing the talking-circuit across the connector-conductors. In this way the calling-current is automatically sent out over the line to be called and then cut off after a predetermined time, which time depends upon the size and number of the holes w^2 in the inner tubes w' of the switch devices.

When the frame B of the main circuit-changer is moved, it also tips the delay-action circuit closer and breaker C, whereby the mercury within its inner tube flows out of the open 5 end of the inner tube and rests at the corresponding end of the outer tube. So soon as the magnet M' is demagnetized, the spring v³ lifts the main circuit-changer V and with it the frame B, thereby restoring the circuit- 10 breaker C to the normal position. At this moment the mercury flows down around the inner tube, and thus closes the circuit between the wires p and e⁴, thereby closing the branch circuit over the conductors x⁵ x⁶ x⁷ 15 and energizing the restoring-magnet E⁴, whereby the shutter of the clearing-out annunciator is restored to its normal position. When the mercury has passed through the holes in the inner tube of the switch device 20 to the bottom of said inner tube, the branch circuit is again broken. The lines are now ready for conversation, and when the same is completed and the subscribers or either of them have rung off the clearing-out drop is 25 operated by the energizing of its coils E³ in the usual manner, the shutter remaining down until the next use of the plug in making another connection, whereupon the shutter is restored by the circuit-closing device C, 30 as previously described.

It will be noted that by this invention the operator has only to insert the answering-plug in the socket of the calling-line, listen at the central-station phone for the message 35 of the calling subscriber, and then insert the connecting-plug in the socket of the line to be called, all other steps necessary in making a connection being performed automatically.

40 In Fig. 4 I have shown a modified embodiment of my invention, wherein the circuit-changer which throws the calling-current onto and off the line to be called is changed so that the mercurial switch devices are not included in the talking-circuit. In this construction the tongue B³, pivoted to the frame B² of the main circuit-breaker, is released 45 from contact with the frame of the circuit-breaker W' by means of an electromagnet M², which co-operates with its armature m', secured to the tongue B³. The coils of the magnet M² are included in a local circuit which includes the source of calling-current R², a simple switch w⁷, and a delay-action 50 circuit closer and breaker C'. The latter is somewhat similar to one of the switch devices employed in the circuit-changer, hereinabove described, the difference being that it is not provided with terminals equivalent 55 to those indicated at s³ and r, Fig. 2. The construction of the said delay-action circuit closer and breaker C' will be understood from Fig. 5. It is mounted in trunnions and is provided with an end A', arranged to be engaged 60 by a nose b² of the main circuit-changer, and is held in its normal position by a spring c². The circuit-changer W' comprises two

switch-arms w⁸ w⁹, each pivoted at one end, the arm w⁸ being arranged to engage either the contact-point n³ or the contact-point r³, 70 while the switch-arm w⁹ is arranged to engage either the contact-point o³ or the contact-point r⁴. The said contact-points n³ o³ are connected to the wires n' o', respectively, of the connector-conductors, while the pivotal 75 points of the switch-arms w⁸ w⁹ are connected, respectively, to the wires n o of the connector-conductors. The contact-points r³ r⁴ are two terminals of the local circuit which contains the source R² of the calling-current. 80 The two switch-arms w⁸ w⁹ and the switch w⁷ are connected to the frame w¹⁰, which is acted on by the tongue B³, said frame being held in its normal position by a spring w¹¹. The operation of this apparatus is as follows: When 85 the main circuit-breaker V is drawn down by the action of its magnet M', the frame w¹⁰ is also forced down by the tongue B³ against the action of the spring w¹¹, thereby moving the three switch-arms w⁷ w⁸ w⁹, the latter two, 90 (w⁸ w⁹) leaving the contact-points n³ o³, respectively, and engaging the contact-points r³ r⁴, respectively, while the switch-arm w⁷ engages the contact-point r⁵. In this way the connector-conductors n n' o o' are opened and 95 the source of calling-current R² connected to the terminals of the connecting-plug S² over the wires n o. At the same time the delay-action circuit closer and breaker C' is tipped by the nose b² on the tongue B³ and then released, whereby the said circuit closer and breaker C' is allowed to return to its normal 100 position. When it is first tipped, the mercury runs out of the inner tube, and thus breaks the local circuit of the battery R² at the terminals m² r', Fig. 5. By the time the circuit closer and breaker again returns to its normal position the local circuit is closed at the switch-arm w⁷, and hence when the mercury has returned through the holes in the 105 inner tube it closes the local circuit through the terminals m² r', and thus completes the local circuit. Thereupon the magnet M² is energized and attracts its armature m', thus drawing the tongue B³ to one side and releasing 110 the frame w¹⁰, which is then drawn up to its normal position by the spring w¹¹, thus cutting off the local circuit which supplies the calling-current and again closing the talking-circuit across the connector-conductors. 115

In the modification shown in Fig. 6 the delay-action switch device C of Fig. 1 is omitted and the branch circuit which includes the coils of the restoring-magnet E⁵ is arranged to be closed by a switch-arm v³, connected to the other switch-arms of the main circuit-changer, the said switch-arm v³ carrying the armature v⁴ of the magnet M³ and being arranged to wipe over a contact device e⁵ during the movement of said switch-arm v³ in 120 either direction, the contact between the said switch-arm v³ and the contact device e⁵ being merely momentary. The local circuit which 125 contains the source R³ of calling-current

stands open at the terminals r^6 r^7 and is arranged to be switched onto the conductors n^6 , leading to the connecting-plug S^2 , by the circuit-changer W^2 , which in this case consists of two switch-arms w^{12} w^{13} , connected by a frame w^{14} , normally drawn upward by a spring w^{15} and arranged to be engaged by a tongue B^4 , pivoted to the frame B^5 of the main circuit-changer V^1 . The tongue B^4 is provided with an armature m^3 , whereby it is drawn aside to permit the return of the frame w^{14} to its normal position, the armature being acted upon for this purpose by a magnet M^4 , included in a grounded branch from the local circuit, which branch contains a source R^4 of direct current. At the substation the telephone hook-lever K , which is connected to one limb of the line, is arranged to wipe over a contact k in moving upward, the said contact k being grounded. With this arrangement the source R^3 may be an alternator, if so desired. In this construction the insertion of the connecting-plug S^2 causes the magnet M^3 to be energized and draw down its armature, thereby moving the main circuit-changer and also wiping the end of the switch-arm v^3 over the contact device e^5 , thus first making and then breaking the circuit through the restoring-magnet. This closure of said circuit on the downward movement of the arm v^3 is without function, except in case the drop has accidentally been tripped. The downward movement of the main circuit-changer causes the calling-current from the source R^3 to be sent out upon the line to be called. As soon as the subscriber at the called station takes the receiver off its hook K the latter moves upward, temporarily closing the grounded circuit through the magnet M^4 , and thereby drawing the tongue to one side and releasing the frame w^{14} , which is returned to its normal position by its spring, thereby cutting off the calling-current and closing the talking-circuit across the connector-conductors.

The construction shown in Fig. 7 differs from that in Fig. 6 in employing a source R^5 of calling-current which supplies direct instead of alternating current. Hence this source serves to energize the magnets M^5 when the subscriber closes the grounded circuit temporarily by the removal of the substation-telephone. For this reason the battery shown at R^4 in Fig. 6 is not required in the construction shown in Fig. 7.

Having thus fully described my invention, what I claim as new, and desire to secure by Letters Patent, is—

1. In a telephone system, the combination with the substation-jacks, a pair of plugs, their connecting-conductors, and a central-station telephone, of connections between the said telephone and the connecting-conductors, a clearing-out annunciator, circuit-changing means operated by the insertion of the connecting-plug in a jack and arranged when operated to substitute the clearing-out an-

nunciator for the central station in the talking-circuit, a source of calling-current, call-circuit-closing mechanism for connecting said source with the substation-line to be called, a connecting device between the circuit-changing means and the said call-circuit-closing mechanism, whereby the latter is actuated by the former, releasing mechanism for releasing the said call-circuit-closing mechanism from the control of said connecting device, and means for returning the call-circuit-closing mechanism to its initial position. 70 75

2. In a telephone system, the combination with the substation-jacks, a pair of plugs, their connecting-conductors, and a central-station telephone, a holder for the answering-plug when not in use, means operated by the removal of the answering-plug from its holder 85 for connecting the central-station telephone with the calling-line, a clearing-out annunciator, circuit-changing means operated by the insertion of the connecting-plug in a jack for substituting the clearing-out annunciator 90 for the central-station telephone in the talking-circuit, a source of calling-current, call-circuit-closing mechanism for connecting said source with the substation-line to be called, a connecting device between the circuit-chang- 95 ing means and the said call-circuit-closing mechanism whereby the latter is actuated by the former, releasing mechanism for releasing the said call-circuit-closing mechanism from the control of said connecting device, and 100 means for returning the call-circuit-closing mechanism to its initial position.

3. In a telephone system, the combination with the substation-jacks connected to the respective substation-lines, jack-sockets for 105 said jacks and a pair of plugs, comprising an answering-plug and a connecting-plug, the latter having a conductive portion to engage the jack-socket when inserted therein, of a pair of delay-action circuit-changers, connect- 110 ing-conductors from said delay-action circuit-changers to the terminals of the two plugs, a source of calling-current, a local circuit in which said source is inclosed, said circuit having its terminals connected to the delay-action 115 circuit-changers, a central-station telephone, an electric self-restoring clearing-out drop, a pair of branch conductors from the connector-conductors of the answering-plug, a main circuit-changer for interchangeably connecting 120 the central-station telephone and the main coil of the clearing-out drop to the branch conductors of the answering-plug, a holder to receive the answering-plug when not in use, a switch in one of the branch conductors, 125 said switch being arranged to be held open when the answering-plug is in the holder, an electromagnet for operating the main circuit-changer, a local circuit-changer-circuit in which are included the coils of the said elec- 130 tronmagnet, the sockets of the jacks and conductive portion of the connecting-plug, means for energizing said circuit, a branch from said local circuit-changer-circuit, in parallel with

the coils of the electromagnet, and including the restoring-coils of the clearing-out drop, a circuit-closer included in the said branch conductor and arranged to be operated by the 5 main circuit-changer, and a connecting device between the main circuit-changer and the delay-action circuit-changers, whereby the latter are set in action by the former.

4. In a telephone system, the combination 10 with the substation-jacks, a pair of plugs, their connecting-conductors, a central-station telephone, connections between said central-station telephone and the connecting-conductors, and a clearing-out annunciator, of a 15 main circuit-changer arranged to interchange the central-station telephone and the clear-

ing-out annunciator in the talking-circuit, a source of calling-current, means operated by the insertion of the connecting-plug in a jack for operating the main circuit-changer and 20 switching the source of calling-current onto the line with which the terminals of the connecting-plug are connected, and means actuated by the called subscriber for cutting off the source of calling-current from said line. 25

In testimony whereof I affix my signature in presence of two witnesses.

GEORG RITTER.
